HUMIDIFIER

Kenneth A. Harmon, Longmeadow, Mass., assignor to Wico Electric Company, West Springfield, Mass., a corporation of Massachusetts

Application April 7, 1938, Serial No. 200,742

2 Claims. (Cl. 237—78)

This invention relates to an improved humidifier adapted for attachment to a radiator and arranged for the evaporation of water by heat derived from the heating fluid supplied to the 5 radiator.

The invention has for an object the provision of a humidifier, which is constructed for attachment to the casing of the steam inlet valve of a radiator, after the bonnet of such casing together with the valve, the stem whereof is 10 mounted in the bonnet, has been removed.

The invention also has for an object the provision of a humidifier in the nature of a water-jacketed steam dome or, more particularly, a 15 central steam dome structure surrounded by a water chamber.

The invention also has for an object the provision of a humidifier which may be quickly and easily installed, even by the unskilled without the use of special tools and without requiring disconnection of the steam piping or movement of the radiator. All that is necessary is to unscrew the aforesaid bonnet and to screw 20 in the humidifier into the hole left by the removal of the bonnet.

The invention also has for an object the provision of a humidifier having a steam dome for direct connection to the radiator inlet valve in such a way that the first steam entering from 30 the inlet pipe will pass into the dome of the humidifier and initiate the vaporization of water prior to the heating up of the radiator.

Other objects and advantages will appear as the detailed description proceeds and will be 35 pointed out in the appended claims.

The invention will be disclosed with reference to the accompanying drawing, in which:

The figure is an elevational view with parts in 40 section, showing a humidifier, embodying the invention, applied to the inlet valve of a radiator.

Referring to this drawing, a portion of the inlet end of a conventional form of steam radiator is shown at 5. The steam supply pipe is shown in part at 6, as connected to the lower end of a valve casing 7. The side outlet of casing 7 is connected by a union 8 with the inlet pipe 9 of the radiator. The casing 7 has the usual partition 10 with an opening 11 therethrough. The usual valve, which controls this opening 11 is removed. Such valve has its stem mounted in a bonnet casting which is threaded into the upper screw threaded opening 12 of casing 7. One simply unscrews this bonnet casting and the valve is carried with it, leaving the

opening 12 free to receive the humidifier of this invention.

The humidifier is essentially a water-jacketed steam dome. The dome comprises an upstanding, hollow member 13 of circular cross section 5 closed at its upper end by a hemispherical top 14. The lower end of the dome member 13 is threaded as at 15 to fit the opening 12 in valve casing 7 and has a flange 16 to abut the top wall of such casing. The chamber 17 within the dome 10 is open at its lower end and in constant communication with the interior of the valve casing. The open lower end of chamber 17 lies directly above the inlet pipe 6, so that steam rising through this pipe has a straight and direct 15 course through opening 11 into the open lower end of the chamber 17 within the dome. So also the water of condensation in the dome has a direct vertically-downward path into pipe 6.

The dome 13 is surrounded by a water space 20 18 formed within a more or less cup-shaped member 19 which is integrally connected to the dome near the lower end thereof. This member 19 is made as large in diameter as it can be and still clear the end wall of the radiator. The 25 walls of member 19 and of dome 13 are preferably made thin and of good heat conducting material, such as aluminum for example. The design is such that the parts described may be conveniently and economically formed by die 30 casting, leaving as the only machining operation the formation of the threaded lower end 15.

A cover of any suitable form is usually provided. Thus, a metal cover 20 rests on the upper edge of member 19 and is provided with a series 35 of lugs 21 which extend inside member 19 to engage the inner wall thereof and hold the cover from lateral displacement. Cover 20 has a series of openings 21 therethrough to enable escape 40 of vapor from chamber 18. The cover is also provided with a suitable handle, such as the knob 22.

To install the humidifier all that is necessary is to remove the bonnet of the valve casing and screw the threaded lower end 15 of the humidifier into the threaded hole 12. The removal of the bonnet carries with it the valve and the stem thereof. An ordinary monkey wrench is the only tool needed for this work and the work can readily be performed by anyone since it does 45 not require any special skill. It is not necessary, as it is with some of the prior art devices, to disconnect the steam piping and move the radiator to enable insertion of the humidifier between the valve and radiator.

The humidifier, having been installed and chamber 18 filled with water, its operation commences immediately on the entrance of the first steam from inlet pipe 6. There is no delay. The 5 first steam rises directly into the dome chamber 17 and evaporation of water in chamber 18 soon proceeds. The location of the steam dome is of special importance where the humidifier is used in connection with radiators which are supplied 10 with steam by oil or gas fired boilers, automatically controlled by a thermostat. In such cases, steam is supplied only intermittently to the radiator. Many times the steam is on only for short intervals. At times, only part of the radiator 15 warms up. Therefore, for use with heating systems of this type, it is essential that the humidifier receive an early and concentrated supply of steam and the described arrangement accomplishes this purpose.

20 The humidifier is designed to be highly efficient as a water evaporating means. There is direct thermal contact between the metal walls of the humidifier and the water. Also, such walls are made very thin (from $\frac{1}{16}$ to $\frac{3}{16}$ of an inch) and 25 they are constructed of metal such as aluminum, which is a good conductor of heat. The steam in the dome 13 of the humidifier is thus separated from the water in the evaporating chamber 18 only by a very thin wall of metal having high 30 heat conductivity. The heat exchange between steam and water is thus very efficient and it takes place quickly. Some evaporation also occurs from the outer wall of the water chamber which is heated from the dome but the main reliance 35 is placed on the dome itself. The outer wall of the humidifier also serves to some extent as a radiator, heating the surrounding air and supplementing to some extent the radiator.

The invention thus provides a humidifier of simple construction, capable of being made by die casting and thus of being provided in quantities at low unit cost. These humidifiers may be sold at low cost so as to be easily within the 5 means of any householder who may thus purchase as many as he requires for his living rooms and install them himself. Thus, one who is unable to afford a complete air conditioning installation, may for a few dollars secure many of 10 the advantages of such an installation by the use of a number of the humidifiers of this invention distributed among the living rooms of his house. These humidifiers are exceptionally efficient and by their arrangement and location are designed 15 to receive a quick and concentrated application of steam to initiate the evaporation of water at the very start of the warming up of the radiator.

What I claim is:

1. The combination with the inlet valve casing 20 of a radiator, said casing having an inlet and an outlet opening, of a hollow dome having a single opening, and so connected to said casing that the opening of the dome lies opposite and in line with the inlet opening of said casing, and a wall en- 25 compassing said dome and forming with the latter a water-receiving chamber.
2. The combination with the casing of the inlet valve of a radiator, said casing having inlet and outlet openings, and a third opening usually 30 closed by the bonnet of the valve, of a humidifier comprising a water-jacketed steam dome having a single open end connected to said third opening to receive steam therefrom.
